UNITED STATES PATENT OFFICE.

ANTON F. SCOW, OF ST. JOSEPH, MICHIGAN.

IMPROVEMENT IN BASKET-FORMERS.

Specification forming part of Letters Patent No. 138,765, dated May 13, 1873; reissue No. 5,757, dated February 10, 1874; application filed December 31, 1873.

To all whom it may concern:

Be it known that I, ANTON F. SCOW, of St. Joseph, county of Berrien, State of Michigan, have invented a new and Improved Basket-Former; and declare the following to be a full, clear, and complete description thereof, reference being had to the accompanying drawings.

My invention relates to an improvement in basket-forms; and consists in a hinged clamp which is combined with adjustable standards for holding the basket-bottom in position for weaving the splints, and in a band which surrounds the lower end of the form, said band being provided with a suitable number of dovetailed grooves, in which move dovetailed clamps for holding the standards in place.

In the drawings, Figure 1 is a side elevation of my invention. Fig. 2 is a plan view of the same; and Fig. 3, details of the clamps, in which—

A B represent the foundation or frame which supports the form and my improvements, it being made of wood or any suitable material, and of any size required. C C represent adjustable standards, which slide through the frame A B, and are provided with slots E for receiving the set-screws D; which hold the standards at the required height for different-sized basket-forms. A metal clamp, X, is pivoted to one of the standards C at F, so as to swing up or down, and its other end is provided with a slot, I, as shown by dotted lines, to receive a set-screw, H, which holds the clamp to the standard, and the slot therein allowing the clamp to be adjusted to or from the form M. This form is pivoted to a standard, V, in the usual manner, so as to rotate, and the bottom J of the basket is held closely to it by a spring-clamp, K, which passes through the curved clamp X. If, however, the clamp X is made of spring-metal, the clamp K may be substituted by any suitable stationary bearing to press against the bottom J. The lower end of the form is provided with a band, O P, corresponding in thickness to the thickness of the standards of the bas-

ket, for the purpose of preventing the ends of said standards from catching the hands and clothes of the operator, and for the purpose of providing a suitable support for the catches T, which slide back and forth in a groove made transversely in said band for the purpose. The grooves in this band are dovetailed in shape, and the clamps sliding in them are correspondingly counter-shaped.

In the drawings are shown but a limited number of these catches upon the band O P, but the number provided in the working-machine corresponds to the number of basket-standards employed. By this means the making of a hole through the bottom J is avoided, while at the same time the band O P prevents the lower ends of the splints from catching the clothing or hands of the operator, and forms a convenient support for the latches which hold the splints while weaving.

To change the devices for a larger or smaller form, the set-screws D must be loosened, which will permit the standards C to be raised or lowered. The bottom is held to the form M by means of the set-screw H and clamp X, the clamp X being swung over back on pivot F when the form M has to be removed.

I am aware of a device patented jointly by J. B. Sweetland and E. C. Goodrich, December 12, 1865. I therefore do not claim, broadly, the employment of a spring-clamp for retaining the extremities of the standards; but

What I claim is—

1. The curved clamp X, with stationary or adjustable standards C, when used to hold the bottom J to the form M, substantially as set forth and shown.
2. The combination of the band O P, provided with the dovetailed grooves Q and the dovetailed sliding clamps for retaining the ends of the standards N, substantially as shown and described.

ANTON F. SCOW.
